UNITED STATES PATENT OFFICE.

SAUL STEINMAN, OF SHELTON, CONNECTICUT.

SIGN HOLDER.

Application filed March 20, 1926. Serial No. 96,241.

This invention relates to an improved sign holder, and it is particularly designed to a holder of this class adaptable for supporting show cards, advertising signs, and equivalent display means in a position for display.

One object of the invention is the provision of an exceedingly and inexpensive simple structure which is such as to effectively accomplish the desired results and so constructed as to render it comparatively rigid, easily adjusted, and such that it may be folded into compact package for shipping and storing purposes.

Briefly, the invention has reference to a conventional show window standard, a novel adjustable sign supporting frame, and a novel coupling between the frame and the standard.

The features and advantages derived from a construction of this kind will become more readily apparent from the following description and drawings.

In the accompanying drawing forming a part of this application, and in which like numerals are employed to designate like parts throughout the same:

Figure 1 is a side view of a complete sign holder constructed in accordance with this invention,

Fig. 2 is a front elevation of the sign frame,

Fig. 3 is a perspective view of one of the details of said frame,

Fig. 4 is a perspective view of the novel coupling between the frame and the standard, and

Fig. 5 is a section through the detail shown in Fig. 3.

Referring to the drawings in detail, the reference character 1 designates, generally, the standard, 2 designates the special coupling, and 3 the sign holding frame.

The standard 1 comprises a suitable base 4 and an upright 5 of hollow tubular form, and an adjustable rod 6. The lower end of the rod telescopes into the upright 5 and is held in various adjusted positions by a set screw 7. It will be noted also that the upper end of the rod 6 is screw threaded at 8.

The coupling 2 as shown in Fig. 4, is of general right angular form and comprises a single strip of material 9 bent upon itself at one end as indicated at 10 to provide a short overlapping ply 11. The opposite end is bent upwardly at 12 and disposed at an approximate acute angle with respect to the

body portion 9. The portions 9 and 11 are formed with a screw threaded hole which is threaded onto the end 8 of the rod 6. By preference, clamping nuts are provided here for maintaining the coupling in place.

The frame 3 comprises an adjustable support which is made up of a lower section 13 and an upper section 14, both sections being in the form of flat metal strips and being provided at their outer ends with horizontally disposed sleeves 15 of rectangular cross section. The upper end of the section 13 is provided with a special head 16 having a passage on one side for reception of the part 12 of the aforesaid coupling and having a passage on the opposite side for slidable reception of the sliding section 14 of the support.

The lower end of this section 14 may be directed to provide a stop 17. Cooperable with the sleeves 15 are longitudinally adjustable card gripping members 18. Each member, as shown in Figs. 3 and 5, comprises a pair of metal strips provided with complementary guide channels 19 and 20. The channel 19 is carried on the upper edge of one member for instance, and the channel 20 is carried on the lower edge of the complementary member. The two strips are stamped or pressed into the shapes shown in Fig. 5 and a firm but sliding connection is thus provided which permits the two strips to be readily maintained in different adjusted positions to which they are moved.

The outer end of each metal strip is offset at 21 and terminates in a card gripping hook 22. From the foregoing it will be seen that the standard 1 is more or less of conventional design, being somewhat similar to the customary standards employed in store windows for holding various kinds of supporting heads. The coupling 2, appears to be novel and provides a unique connection between the sliding rod of the standard and the novel supporting head or sign holding frame. It maintains the frame in an inclined position to facilitate supporting of the card.

The novel way in which the sliding sections of the card gripping members 18 are pressed into shape and engaged with each other permits the devices of the unit to be slid through the respective sleeves 15 and then permits respective adjustment of the parts of the members themselves. No doubt, by carefully considering the description in

connection with the drawings, persons familiar with structures of this class will be able to obtain a clear understanding of the same. Therefore a more lengthy description is thought unnecessary.

While the preferred embodiment of the invention has been shown and described in detail, it is to be understood that minor changes coming within the field of the invention claimed, may be resorted to if desired.

Having thus described my invention, what I claim as new is:—

1. In a sign holder of the class described, a special coupling adapted to serve as a connection between a sign holding frame and a standard, wherein the standard includes a vertically extensible rod having its upper end screw threaded, said coupling comprising a strip of metal bent at one end to provide an upwardly inclined part to be en-

gaged with said frame, and having its opposite end bent into overlapping relation with the central body portion, said overlapping end and body portion being formed with aligned screw threaded holes to thread onto the upper end of the aforesaid rod.

2. In a sign holder of the class described, a standard comprising a vertically adjustable rod having its upper end screw threaded, a sign holding frame, and a coupling between said frame and said rod, said coupling being in the form of a one-piece body of right angular form, one portion of the body being disposed in a horizontal plane and being formed with a screw threaded opening threaded on the upper end of said rod, and the other portion of the body extending upwardly from the horizontal portion and being detachably connected with said frame.

In testimony whereof I affix my signature.

SAUL STEINMAN.
